EVAPORATIVE COOLER

Robert L. Koble, Jr., Phoenix, Ariz., assignor to McGraw-
Edison Company, Milwaukee, Wis., a corporation of
Delaware

Continuation of design applications Ser. Nos. 61,456 and
61,457, July 21, 1960. This application Nov. 23, 1962,
Ser. No. 72,586

Term of patent 14 years

(Cl. D62—4)

fig.3

fig.4

FIG. 1 is a front perspective view of an evaporative cooler showing my new design; FIG. 2 is a reduced rear perspective view thereof; FIG. 3 is a front perspective view of an evaporative cooler showing a modification of said design; and FIG. 4 is a reduced rear perspective view of the design shown in FIG. 3.

The undisclosed sides are substantially the same in appearance as the respective sides shown.

This application is a continuation of my co-pending applications, Serial Nos. D. 61,456 and D. 61,457, filed July 21, 1960, and now abandoned.

The conventional fabric which is partially shown in FIGS. 1 and 3, is understood to continue throughout the unshaded areas of said panel.

I claim:

The ornamental design for an evaporative cooler, substantially as shown and described.
